ELECTRONIC DISCHARGE DEVICE FOR
ELECTRONIC MULTIPLICATION

Maurice Arditi, Boulogne-Billancourt, France, assignor to International Standard Electric Corporation, New York, N. Y., a corporation of Delaware

Application April 1, 1943, Serial No. 481,509
In France July 25, 1941

Section 1, Public Law 690, August 3, 1946
Patent expires July 25, 1961

7 Claims. (CL 250—175)

1

The present invention relates to electronic discharge devices controlled by electric and magnetic fields, such as for example devices employing in cascade one or more stages of secondary electronic emission.

It is customary, in devices in which electrons are multiplied by successive secondary emissions, to control the primary and secondary electronic beams by means of an electric field which accelerates the electrons as they leave an emitting electrode and of a magnetic field which deflects each electron beam toward the next emitting or collecting electrode. For this purpose, generally, a series of non-emitting electrodes is associated with a series of primary and secondary-emission electrodes and the distribution of potentials between these series of emitting and non-emitting electrodes is such that it creates, in the space in front of the electrodes, electric potential gradients aiding the extraction of secondary electrons from the various targets under the impact of electrons from the preceding target. A transversal magnetic field is applied in this space to deflect the electrons emitted by one target towards the next target. The acceleration and deflection of the electrons are generally obtained simultaneously through the combined action of the two electric and magnetic fields.

The electric potential gradients required for driving the emitted electrons from stage to stage are, as a rule, not uniform between the various emitting and accelerating electrodes. This entails a dispersion of electrons which is harmful to the efficiency of the device owing to the defocusing of the electronic paths, and on the other hand it produces a certain interfering background noise or "obscurity" current due to the direct passage, from the cathode to the anode, of erratic ions or electrons engendered by the decomposition of the material of the (photoelectric or thermionic) cathode.

The main object of the present invention is to provide structures of electronic discharge devices of this type which are free of the above mentioned disadvantages and, more specifically, structures of such electronic discharge devices in which means are provided for completely separating the two functions of "acceleration" and "deflection" of the electrons.

These and other objects are accomplished, ac-

cording to the invention, by the arrangement and combination of elements set forth in the following description, defined in the appended claims and illustratively exemplified in the accompanying drawings, in which

5 Fig. 1 is a diagram of an electron multiplier device, according to the invention, from which most of the details of physical construction, the vessel, the supporting connections of the electrodes, the magnet or electromagnet furnishing the transversal magnetic field and other elements which are not necessary for an undertaking of the invention, have been omitted for the sake of simplicity;

10 Fig. 2 is a further simplified diagram of a modified structure;

15 Fig. 3 is a perspective view, certain parts being broken away or shown in section, of a third embodiment of an electron multiplier according to the invention, no electrical connections inside of 20 the tube being shown in this figure;

25 Fig. 4 is a perspective view of the screen 5a of the electron multiplier of Fig. 3 showing details of the invention.

30 Referring now to the drawing, and first to Fig. 1, a photo-cathode 1 is arranged in a common plane with two secondary-emission electrodes or targets 2—3, and a collecting electrode 4. An electric screen in the form of a box 5 is placed in front of the electrodes 1 to 4. The screen box 5 consists of a non-magnetic metal so that a transversal magnetic field H may cross it. It is provided with two aligned openings 6 and 6', in its front and rear walls, respectively, opposite the photo-cathode 1, to allow passage of a light-beam 7, and with three additional openings 8, 9 and 10 in its front wall opposite the secondary-emission electrodes 2 and 3 and the collecting electrode 4, respectively, to allow passage of the electronic beams. A high electric potential is applied to the entire box 5, so that a zero potential gradient region is created within the box.

35 The potentials to which the various electrodes are raised may be taken from a single potentiometer 11 in the manner shown. The collecting electrode 4 is raised to the same high potential as the screen box 5, and may even be constructed as a part of such box.

40 The photo-cathode 1 is surrounded by a Wehnelt cylinder or other auxiliary electrode 12, and

2

the secondary-emission electrodes 2 and 3 are associated with Wehnelt cylinders, 13 and 14, respectively. These auxiliary electrodes which serve for the concentration and acceleration of outgoing electrons (or for the deceleration of incident electrons) are raised to suitable potentials taken from the potentiometer 11. The auxiliary electrodes 13 and 14 are raised preferably to the same potential. The relative potentials of the various electrodes are preferably so chosen that the impact speeds of the incident electrons on the secondary-emission targets insure a maximum extraction of secondary electrons from the latter. These impact speeds expressed in volts correspond generally to potentials of 500 to 700 volts.

It will be understood that any more or less complex electron-optic structure may be associated with each emitting electrode for the concentration and speed regulation of the electrons.

Means (not shown) are provided to apply to the zero electric potential gradient region within the box 5 a transversal magnetic field H which, in this zero potential region, acts only to deflect the electronic beams from one electrode to the next one. Within the box 5, the electronic beams follow substantially circular paths. No acceleration or deceleration takes place within this box, and, therefore, the interfering ions or electrons emitted by the photo-cathode are unable to pass directly to the collecting electrode 4. The residual current of the device is very small and there is no "obscurity" current on the collecting electrode 4. Any possible contamination of the secondary-emission electrodes 2 and 3 by a direct evaporation of the cathode decomposition products is completely obviated.

The electronic flux from the cathode 1 may be additionally controlled by a grid 15 of usual construction.

Instead of a closed screen box such as 5 (Fig. 1), a screen consisting simply of two spaced apart, suitably perforated, parallel plates 16 and 17 may be used, as shown in Fig. 2. The structure of Fig. 2 is similar to that of Fig. 1 and the same reference characters are used for the corresponding elements. The two screen plates 16 and 17 are raised to the same electric potential, for example by means of a connection 18, so that the electric potential gradient is zero in the region between the two plates 16 and 17 where the deflecting magnetic field H is applied. The operation of the device is, thus, similar to that of the structure of Fig. 1 and its advantages are substantially equivalent.

In Fig. 3, the screen 5a is cylindrical and it is surrounded by two likewise cylindrical grids 20 and 21. Grid 20 acts as a Wehnelt electrode for all the secondary-emission electrodes 2 and 3 and for the collecting electrode 4. The photo-cathode 1a is associated with an individual Wehnelt cylinder 31 serving as a control electrode. Grid 21 acts as an accelerating grid (for the outgoing electrons) and as a decelerating grid (for the incident electrons). The two grids 20 and 21 are deformed at the locations corresponding to the emitting and collecting electrodes in the manner shown at 22, 23, 24 and 25 for grid 20, in order to produce at these points electronic-lens effects for concentrating and focussing the emitted and received electrons. The cylindrical screen 5a has perforation 6a, 8a, 9a, 10a similar to those of the box 5. This is illustrated in Fig. 4. Within the perforated cylinder screen 5a the electric potential gradient is kept at zero as in the case of the box or the plates of Figs. 1 and 2, respectively,

and the transversal magnetic field H is applied in this region by means of a magnet 28, the pole pieces of which surround the structure in the manner shown. Fig. 3 shows, partly cut away, 5 the insulating envelope 27 of the structure, its socket base 28 and the connector plugs 29.

Further, as a modification of the secondary-emission electrode arrangement, Fig. 3 shows, by way of example, the secondary emission electrodes 10 23 and 24 formed on a single curved plate 30, which reduces the number of plugs 29. A control grid 15 may be associated with photo-cathode 1a as shown.

It is obvious that the invention is not limited 15 to the examples shown and described but is capable of numerous modifications and variations within the scope of the following claims.

I claim:

1. An electronic discharge device for secondary emissions comprising a primary emitting electrode, a secondary emitting electrode, and a collecting electrode, all said electrodes being mounted in succession and substantially aligned, electrode means mounted in front of said aligned electrodes for producing a zero potential gradient region beginning a short distance from said aligned electrodes and extending along the path of the electron beams emitted by said aligned electrodes, said electrode means 20 having apertures for the passage therethrough of the electron beams, means adjacent said aligned electrodes and in the short space between said aligned electrodes and said region of zero potential gradient for controlling the speed 25 of the electrons in said beams, and means adjacent said region of zero potential gradient for applying therein a transverse magnetic field for the deflection of the electron beams entering said region.
2. An electronic discharge device as claimed in claim 1 in which said means for controlling the electron speed comprises regulating electrodes adjacent the individual emitting and collecting electrodes respectively for regulating the speed 45 of and concentrating the emitted electrons.
3. An electronic discharge device, as claimed in claim 1 in which said aligned electrodes are substantially in a common plane and said means for producing a zero electric potential gradient region 50 includes two spaced parallel plates consisting of an electrically conductive non-magnetic material, said plates being mounted rearwardly of one another in front of and parallel to said common plane, the plate next to said plane being provided 55 with openings opposite said electrodes to permit the passage of electronic beams into the space between said plates.
4. An electronic discharge device for secondary emissions, comprising a primary emitting electrode, a secondary emitting electrode and a collecting electrode, said electrodes being disposed side by side on a generatrix of an imaginary cylinder, a screen-cylinder defining a zero electric potential gradient region 60 consisting of an electrically conductive, non-magnetic material and having substantially the same axial length but a smaller diameter than said imaginary cylinder, said screen cylinder being located concentrically within said imaginary cylinder in front of said electrodes and being provided with openings opposite the latter, respectively, and means adjacent said region for applying therein a transversal magnetic field for the deflection of the electron beam entering said region.

5. An electronic discharge device, as claimed in claim 4 in which said means for controlling the electron speed comprises, between said screen cylinder and said imaginary cylinder, concentric grids deformed at points opposite said electrodes constituting electron concentrating and electron speed regulating elements for the various emitting and collecting electrodes, respectively.

6. An electronic discharge device according to claim 1 in which the means for creating a zero potential gradient region comprises two metallic members having substantially all corresponding portions of their adjacent surfaces spaced equidistant from one another.

7. An electronic discharge device according to claim 1 in which the means for applying a magnetic field comprises a generator of magnetic flux located adjacent the zero potential gradient region for applying in said region a transversal magnetic field for the deflection by substantially 180° of the electron beams entering said region.

MAURICE ARDITI.
